UNITED STATES PATENT OFFICE

165,110

BOTTLE

Edward Rachins, Brookline, Mass.

Application July 13, 1951, Serial No. 15,854

Term of patent 14 years

(Cl. D58—9)

To all whom it may concern:

Be it known that I, Edward Rachins, a citizen of the United States of America, residing at Brookline, in the county of Norfolk and Commonwealth of Massachusetts, have invented a new, original, and ornamental Design for Bottle, of which the following is a specification, reference being had to the accompanying drawing, forming part thereof.

Fig. 1 is a plan view of a bottle, showing my new design;

Fig. 2 is a front elevation thereof;

Fig. 3 is a side elevation looking to the left of Fig. 2; and

Fig. 4 is a rear elevation of the bottle.

The opposite side of the bottle is similar to the view shown in Fig. 3.

I claim:

The ornamental design for a bottle, as shown and described.

EDWARD RACHINS.
